ROBOT AMUSEMENT RIDE DEVICE

Salvatore Cirami, 75—36 Parsons Blvd., Flushing, N.Y.

Filed Sept. 27, 1961, Ser. No. 66,874

Term of patent 14 years

(Cl. D34—5)

FIG. 1

FIG. 2

FIG. 1 is a front perspective view of a robot amusement ride device embodying my design.

FIG. 2 is a rearward perspective view thereof.

I claim:

The ornamental design for a robot amusement ride device, substantially as shown.
